CLAIM

The ornamental design for packaging with accessory, as shown and described.

DESCRIPTION

FIG. 1 is a front perspective view of packaging with accessory showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The Figures are illustrated to show contrast. One accessory in the packaging is one appearance and the other accessory in the packaging is a different appearance.

The broken lines in the Figures show portions of the packaging with accessory which form no part of the claimed design.
